UNITED STATES PATENT OFFICE.

THOMAS PARKER, OF TORONTO, CANADA, ASSIGNOR OF THREE-FOURTHS
TO JOHN DOUGLAS WRIGHT, FRANCIS FARQUHARSON STUART, AND
ALEXANDER MAXWELL COLQUHOUN, OF SAME PLACE.

PULVERIZER.

SPECIFICATION forming part of Letters Patent No. 529,874, dated November 27, 1894.

Application filed December 8, 1893. Serial No. 493,097. (No model.) Patented in Canada January 4, 1894, No. 44,997.

To all whom it may concern:

Be it known that I, THOMAS PARKER, manufacturer, of the city of Toronto, in the county of York, in the Province of Ontario, Canada, have invented certain new and useful Improvements in Pulverizers, (for which I have obtained a patent in Canada, dated January 4, 1894, No. 44,997,) of which the following is a specification.

10 My invention relates to improvements in pulverizers and the object of the invention is, first, to devise a cheaply constructed and efficient pulverizer, which will rapidly reduce clay, rock or other substances to powder; 15 secondly, to provide means whereby only the completely pulverized clay may be ejected from the machine, and thirdly to provide a means to prevent damp clay when being pulverized from sticking to the bars, projections 20 or walls of the pulverizing chamber and it consists essentially, first, of securing to a main shaft journaled in the end of a suitable chamber three disks one at each end and one intermediately situated between the end 25 disks, the disks having cross rods extending from end to end parallel to the shaft upon which are loosely journaled a series of arms or beaters, which are caused to fly out by the rotary movement of the disks; secondly, of 30 providing at the one end of the machine preferably upon the main shaft a fan, which communicates with the main chamber through a duct, which leads to the bottom of the machine, where it is connected to the chamber 35 by upwardly extending passage-ways and further in providing an exit duct and separator provided with a bolting cloth through which the air is forced, the pulverized clay being designed to be ejected through the exit 40 duct and separator by the fan, and, thirdly, of making the walls of the pulverizing chamber hollow and introducing steam through pipes into such hollow walls, the machine being otherwise constructed as hereinafter more 45 particularly explained.

Figure 1, is a perspective view of my pulverizer with the duct and hopper removed, portions of the end and side being broken

away so as to exhibit the construction. Fig. 2, is a cross section through the chamber, 50 ducts, hopper and separator. Fig. 3 is a longitudinal vertical section through the beaters and fan.

In the drawings like letters of reference indicate corresponding parts in each figure. 55

A, are the end walls, of the chamber, and, B, are the side walls, which are made hollow for the purpose of receiving steam.

B', and, B'', are the outlet and inlet steam pipes connected to the opposite walls, B. The 60 hollow walls are connected together by a pipe, B³, as indicated by dotted lines in Fig. 2.

C, C', is the bottom, which is made in two sections secured together in the center by suitable bolts and to the bottom of the side 65 walls by suitable bolts. To the bottom section, C, I secure a series of projections, c, c', extending across the machine. The bottom, C, C', is supported upon the cross beams, D, D'.

E, is the main shaft of the machine, which is suitably journaled in the ends of the machine. The main shaft E, has secured to it the end disks, F, F, and a central disk, F'.

G, are rods extending from one end to the 75 other through the central disk, F'. These rods are situated near the periphery of the disks and are provided with a series of beaters, H, which are loosely journaled upon the rods. The hubs of the beaters are wider than 80 the beaters and abut each other and there is only one beater extending out from the periphery of each hub, so that each beater will have perfect freedom of movement upon the rod. The beaters, H, extend between the 85 disks from end to end of the rods.

I, is a fan casing, which is secured on one end, A, outside the pulverizing chamber.

J, is a fan, which is secured on the outer end of the shaft, E. The disks, F, and fan, J, 90 are driven from a pulley, K, on the opposite end of the shaft to that on which the fan is situated.

L, is a conveying duct extending upwardly and laterally from the pulverizing chamber 95 into the separator, M. One side of the sep-

arator is provided with a bolting cloth screen, *m*, as indicated by dotted lines. The lower end of the separator is open.

5 *O*, is the feed hopper which is situated at the top of the pulverizing chamber at the right hand side.

10 *P*, is the air duct leading from the bottom of the fan casing, *I*, to beneath the bottom, *C, C'*. *p*, are the passage-ways leading upwardly from the air duct, *P*, through the bottom *C, C'*, into the pulverizing chamber. The passage ways are situated between the spaces swept by the beaters, *H*.

15 Having now described the principal parts involved in my invention I shall briefly describe its operation.

Upon the power being applied to the pulley, *K*, the disks rotate in the direction indicated by arrow and the beaters, *H*, will be caused 20 to fly out into the position shown by dotted lines. The clay, rock or other substances being fed into the hopper, *O*, will be acted upon by the outwardly flung beater so that the material will be readily reduced to powder or pulverized. It will be readily seen that if the rock or clay form any obstruction to the beaters, *H*, that they will on account of being pivoted on the rods, *G*, pass over such rocks or projections but will quickly wear 25 them away on account of the rapidity at which they are rotated. The fan, *J*, being driven also at a high rate of speed will force the air down through the duct, *P*, up through the passage way, *p*, and the pulverized clay from 30 the rock or solid clay will be thrown toward the left hand side of the machine (see Fig. 2) up through the duct, *L*, into the separator, *M*, where part may come in contact with the bolting cloth while the other will pass down 35 into any suitable receptacle, which may be placed beneath such separator. The bolting cloth, *m*, of course allows of the air being blown out through it but prevents any of the pulverized clay from escaping through the 40 opening covered by the bolting cloth.

45 From this description it will be seen that I provide a very effective pulverizer in which the beaters on account of being loosely swung upon the rods, *G*, are not subject to breakage 50 and which will act very effectively with the projections, *c, c'*, formed on the bottom of the pulverizing chamber, so as to rapidly grind up the material. Although I show no steam in the bottom sections it will of course be understood that the heat communicated from 55 the hollow sides will be communicated to such bottom sections, *C, C'*, so as to prevent any sticking of the clay or material upon the projections, *c, c'*, or at the bottom of the pulverizer. The steam will also prevent the damp clay from sticking on the sides as it will serve

to keep the clay at both the bottom and sides perfectly dry should damp clay be placed in the pulverizing chamber.

What I claim as my invention is—

65

1. In a pulverizer the combination with the chamber to receive the material and a shaft journaled in the ends of the chamber and provided with disks, and rods extending between the disks secured in them near their periphery and parallel to the shaft, of a series of beaters having hubs wider than the beaters abutting each other in their supporting rods, such beaters being arranged when the shaft is in motion to extend entirely outside the circle of the disks and rotate in close proximity to the bottom of the chamber and the two series of rounded tapered projections *c, c'*, similarly formed and having the broad end of the projections adapted to co-act with 70 the striking side of the beaters, which pass between them as they rotate as and for the purpose specified.

2. In combination with the chamber, the shaft journaled therein, disks on the shaft and rods extending between the disks, beaters journaled on such rods and abutting each other, the hopper and exit duct in juxtaposition at the top of said chamber, a board situated between the duct and hopper and forming part of each, said duct and hopper extending down in proximity to the beaters, substantially as described.

3. The combination with the chamber, shaft journaled therein, disks on the shaft and rods extending between the end disks and beaters loosely journaled on such rods as specified, of a fan secured on the outer end of the shaft and fan casing having a duct leading from it beneath the pulverizing chamber, such duct having a series of vertical passage-ways extending up into the chamber as and for the purpose specified.

4. The combination with the chamber, shaft journaled therein, disks on the shaft and rods extending between the end disks and beaters loosely journaled on such rods as specified, of the fan, *J*, provided with the casing, *I*, and duct *P*, leading from the casing to beneath the bottom of the pulverizing chamber and provided with vertical passage-ways *p*, leading into the pulverizing chamber, the duct, *L*, secured at the top of the pulverizing chamber and leading into the separator, *M*, which is provided with an opening 110 covered by the bolting cloth, *m*, as and for the purpose specified.
